Specification of Letters Patent.

Patented Apr. 4, 1922.

Application filed December 30, 1920. Serial No. 434,030.

To all whom it may concern:

Be it known that I, ALFRED C. CHRISTOPHERSON, citizen of the United States, residing at Menasha, in the county of Winnebago 5 and State of Wisconsin, have invented a certain new and useful Improvement in Printing Presses, of which the following is a full, clear, concise, and exact description.

My invention relates to printing presses 10 that employ complementary printing members at least one of which is in the form of a cylinder, these printing members being equipped with bearers which limit the extent to which such members may be approached under the influence of printing pressure exerting means which, in accordance with my 15 invention, is so interrelated with the cylinder, or one of the cylinders if both printing members are cylindrical, as to effect the engagement of such cylinder with the complementary printing member with the requisite pressure required in the printing operation. If the printing space defined by the 20 contacting bearers should be too narrow to accommodate the paper being printed upon and the printing form or element that are 25 between the printing members in the printing operation, the aforesaid printing pressure effecting means will yield to permit such separation of the bearers that would 30 avoid any increase in the printing pressure between the printing members. I further provide means for rendering the printing pressure exerting means functionless for its 35 purpose to enable or permit separation of the printing members in the non-printing operation of the press.

The printing pressure exerting means is 40 preferably in the form of spring mechanism which is effective, in the printing operation, to move the printing cylinder member into printing relation with the other member and to maintain the bearers of these members in contact if the printing form and the paper 45 being printed upon together do not exceed the proper printing depth or type height, the spring mechanism yielding to permit a separation of the bearers if the aggregate depth of the printing form and the paper 50 being printed upon is excessive. By the construction of my invention the printing pressure between the printing cylinder member and the complementary printing member of a press cannot exceed the printing pressure exerting force of the spring mecha-

nism, the printing cylinder member that is directly influenced by the spring mechanism yielding, in opposition to the force of the spring mechanism, if the aggregate depth of the printing form and paper is excessive, to 60 a point at which the spring mechanism exerts the printing pressure for which it is designed.

Hitherto separation between the bearers of the printing members of a press, due to 65 the pressure thereon of the printing form and paper having an aggregate excessive depth, was permitted by the springing of structural parts of the press that were liable to retain warped or set shapes. 70

The printing press forming the subject matter of the present application is a form of the invention more broadly covered in my copending application Serial No. 434,029 filed Dec. 30, 1920. 75

I will explain my invention more fully by reference to the accompanying drawings showing the preferred embodiment thereof and in which Fig. 1 is a view in side elevation of one form of printing press constructed in accordance with the invention; Fig. 2 is a sectional view on line 2—2 of Fig. 1; Fig. 3 is a sectional view on line 3—3 of Fig. 2; Fig. 4 is a view looking at one side of the press showing parts thereof on a larger scale, portions being broken away and other portions being shown in section; and Fig. 5 is a sectional view on line 5—5 of Fig. 4. 80

Like parts are indicated by similar characters of reference throughout the different 90 figures.

The main supporting frame 1 of the machine includes a suitable pedestal 2 which may be separately formed from the balance of the frame and assembled therewith by 95 means of the bolts 3. Upright supports 4 carry the rotating shaft 6 of the printing cylinder 7, these supports finding a substantially fixed axis of rotation for the cylinder in the printing operation and another 100 fixed axis of rotation for the cylinder in the non-printing operation. The press illustrated being a hand press, said shaft is equipped with a hand crank 8 for the purpose of effecting the rotation of the cylinder, 105 though it is understood other means may be employed for accomplishing this result. Bearer rollers 9, having fixed axes, are supported by the frame 1 preferably by means of roller bearings 9' and support the re- 110

ciprocating printing bed 10, this bed being adapted to carry the employed printing form 11 of any suitable character. The cylinder 10 is pressed downwardly during the printing operation, as will hereinafter more fully appear, in order that the requisite printing pressure may be exerted by the printing form upon the paper 12 passing through the press.

10 The printing cylinder is provided with the usual bearers 13 at the sides of the press and the bed is provided with the usual bearers 14, also at the sides of the press, upon which the bearers 13 roll as the bed is moved 15 in each printing operation, these bearers, when contacting, defining the normal printing space between the printing members 7 and 10. Coiled springs 15, one upon each side of the press, constitute the preferred 20 means for effecting the desired printing pressure. The upper end of each of these springs has an abutment 16 fixedly assembled with the lower ends of the rods 17 that are themselves fixedly carried by the frame 25 1 from which the rods depend, nuts 18 serving to clamp the abutment 16 against the larger portions of the rods. The lower end of each spring 15 has a floating abutment 19. A rod 20 is in threaded engagement 30 with the abutment 19, there being also lock nuts 21 upon the rod 20 to hold this rod and the abutment 19 in fixed relation. The upper end of the rod 20 is provided with a nut 22 engageable with the top of the corresponding fixed abutment 16. Each abutment 19 and the corresponding bolt nut 22 are so spaced apart that when the spring 15 therebetween is effecting printing pressure, during the printing stroke of the bed, 35 through the elements hereinafter to be described, the nut 22 will not contact with the abutment 16 but when the adjustment is such that the cylinder 7 is to be raised for the non-printing stroke of the bed or to 40 separate the printing members at any desired time the nut 22 will engage the abutment 16 to act as a stop to prevent the spring from exerting printing pressure in order that the cylinder 7 may then be raised 45 50 away from the bed 10.

As illustrated, each spring 15 performs its function through a continuation 23 of the rod 20, this continuation 23 being in snug sliding fit with a vertical opening in 55 the corresponding side of the frame 1 as is also the corresponding support 4. The upper end of each rod continuation 23 is in adjustable threaded connection with the lower side of the corresponding floating 60 block 24 upon the same side of the press with the engaging rod continuation 23. Each floating block 24 supports a bearing 25. A shaft 28 is journaled in both bearings 25. This shaft, in the case of a hand 65 operated press, is provided with a crank 29

by which the shaft may be turned in its aligned bearings 25. Co-axial circular elements 30 are formed or otherwise fixed upon and in eccentric relation to each end of the shaft 28 so that the operations effected by 70 the movements of the crank 29 upon one side of the press are duplicated upon the other side of the press.

For the printing stroke the crank 29 is turned to bring the axis of the eccentrics 75 30 below the axis of the shaft 28. In this adjustment the upright supports 4 are depressed by the eccentrics 30 with respect to the axis of the shaft 28 and against the force of the springs 15 whereby the printing cylinder 7 is pressed toward the complementary printing member with a yielding force that is determined by the springs, the eccentrics 30 serving so to position the slides 24 and the floating abutments 19 connected therewith as to define working clearances between the abutments or stops 22 and the fixed abutments 16 so as to permit the springs 15 to exert printing pressure to an extent that is limited only by the bearers 13 80 and 14 or by the printing form and paper passing or interposed between the printing members. The spring effected printing pressure is maintained during the printing stroke of the printing bed 10 that is effected during the rotation of the cylinder 7 in one direction and through the intermediation of the spur gear 35 co-axial with said cylinder and the rack 36 fixed upon one side 85 of the printing bed. During the non-printing stroke of the bed the cylinder is to be raised sufficiently to separate the bearers 13 and 14, in accordance with common practice. The extent to which the cylinder 7 is raised is insufficient to uncouple the gear 90 elements 35 and 36 so that when the cylinder 7 is reversely rotated in the non-printing stroke the bed 10 may be moved in an opposite direction from that in which it was moved in the printing stroke. In order 95 to raise the cylinder 7 for the non-printing stroke the crank 29 is moved to raise the eccentrics 30. In the first part of the raising movement of these eccentrics the bolt nuts 22 are engaged with the top sides 100 of the abutments 16. When these bolt nuts have engaged these abutments the springs 15 can no longer function to exert downward pressure upon the blocks 24 so that, upon continuation of the eccentric raising 105 movement of the crank 29, the upright supports 4 will be raised from the bed 10 only to such an extent that the gear elements 35 and 36 will not be unmeshed but to an extent which will secure the desired separation of the bearers 13 and 14 for the non-printing operation.

The spacing between the bolt nuts 22 and the abutment 16, that is present when the springs 15 are performing their function, is 110

sufficiently small in relation to the degree of eccentricity of the shaft 28 and the eccentricities 30 that said bolt nuts will encounter the abutments 16 during the first small portion 5 of the cylinder raising movement of the crank 29 so that upon further movement of this crank the eccentricities 30 may function to raise the cylinder 7 unopposed by the action of the spring.

10 It will be observed from the foregoing description that the spring mechanism is adjustable to determine the degree of printing pressure that is to be exerted thereby whereby such pressure may be suited to the character 15 of the printing to be performed and the nature of the printing elements employed.

While I have herein shown and particularly described the preferred embodiment of my invention I do not wish to be limited to the precise details of construction shown as changes may readily be made without departing from the spirit of my invention, but having thus described my invention I claim 25 as new and desire to secure by Letters Patent the following:—

1. A printing press including two printing members one of which is a rotatable cylinder mounted to be movable toward and from 30 the other member and to have a substantially fixed axis of rotation while printing, each printing member being provided with bearers engaging the bearers upon the other; printing pressure exerting means operating 35 upon said cylinder to maintain the bearers in contact during the printing operation and permitting separation of the engaging bearers to prevent undue increase of the printing pressure; and means for separating the 40 engaging bearers.

2. A printing press including two printing members one of which is a rotatable cylinder mounted to be movable toward and from the other member and to have a substantially 45 fixed axis of rotation while printing, each printing member being provided with bearers engaging the bearers upon the other; printing pressure exerting means operating upon said cylinder to maintain the bearers 50 in contact during the printing operation and permitting separation of the engaging bearers to prevent undue increase of the printing pressure; and means for separating the engaging bearers and for then depriving 55 the printing pressure exerting means of its function.

3. A printing press including two printing members one of which is a rotatable cylinder mounted to be movable toward and 60 from the other member and to have a substantially fixed axis of rotation while printing, each printing member being provided with bearers engaging the bearers upon the other; printing pressure exerting spring 65 means operating upon said cylinder to

maintain the bearers in contact during the printing operation and permitting separation of the engaging bearers to prevent undue increase of the printing pressure; and means for separating the engaging bearers. 70

4. A printing press including two printing members one of which is a rotatable cylinder mounted to be movable toward and from the other member and to have a substantially fixed axis of rotation while printing, each printing member being provided with bearers engaging the bearers upon the other; printing pressure exerting spring means operating upon said cylinder to maintain the bearers in contact during the printing operation and permitting separation of the engaging bearers to prevent undue increase of the printing pressure; and means for separating the engaging bearers and for then depriving the printing pressure exerting means of its function. 80

5. A printing press including two printing members one of which is a rotatable cylinder mounted to be movable toward and from the other member, which is in the form 90 of a reciprocating bed, and to have a substantially fixed axis of rotation while printing, each printing member being provided with bearers engaging the bearers upon the other; printing pressure exerting means operating upon said cylinder to maintain the bearers in contact during the printing operation and permitting separation of the engaging bearers to prevent undue increase of the printing pressure; and means for separating the 95 engaging bearers.

6. A printing press including two printing members one of which is a rotatable cylinder mounted to be movable toward and from the other member, which is in the form 100 of a reciprocating bed, and to have a substantially fixed axis of rotation while printing, each printing member being provided with bearers engaging the bearers upon the other; printing pressure exerting means operating upon said cylinder to maintain the bearers in contact during the printing operation and permitting separation of the engaging bearers to prevent undue increase of the printing pressure; and means for separating the 105 engaging bearers and for then depriving the printing pressure exerting means of its function.

7. A printing press including two printing members one of which is a rotatable cylinder mounted to be movable toward and from the other member, which is in the form 110 of a reciprocating bed, and to have a substantially fixed axis of rotation while printing, each printing member being provided with bearers engaging the bearers upon the other; printing pressure exerting spring means operating upon said cylinder to maintain the bearers in contact during the printing operation and permitting separation of the 115 printing operation and permitting separation of 120

the engaging bearers to prevent undue increase of the printing pressure; and means for separating the engaging bearers.

8. A printing press including two printing members one of which is a rotatable cylinder mounted to be movable toward and from the other member, which is in the form of a reciprocating bed, and to have a substantially fixed axis of rotation while printing, 10 each printing member being provided with bearers engaging the bearers upon the other; printing pressure exerting spring means op-

erating upon said cylinder to maintain the bearers in contact during the printing operation and permitting separation of the engaging bearers to prevent undue increase of the printing pressure; and means for separating the engaging bearers and for then depriving the printing pressure exerting means of its function.

In witness whereof, I hereunto subscribe my name this 24th day of December A. D., 1920.

ALFRED C. CHRISTOPHERSON
